DOUBLE PINWHEEL TOY

Paul Millard Lewis, Chicago, Ill.

Application May 14, 1957, Serial No. 46,148

Term of patent 7 years

(Cl. D34—15)

Fig. 1 is a front elevational view of a double pinwheel toy, showing my new design, the rear having substantially the same appearance;

Fig. 2 is a side elevational view thereof; and

Fig. 3 is a top plan view thereof.

A portion of the stick has been broken away in Figures 1 and 2 for convenience in illustration.

I claim:

The ornamental design for a double pinwheel toy, as shown and described.
